CINEMATOGRAPHIC FILM WINDING
MECHANISMTakeo Shimizu, Tokyo, Japan, assignor to Zaidan
Hojin Rikagaku Kenkyujo, Tokyo, JapanApplication March 18, 1937, Serial No. 131,742
In Japan March 25, 1936

1 Claim. (Cl. 88—18.7)

This invention relates to an apparatus that makes rewinding of the film in the cinematographic projector unnecessary, consisting of a vertical feeding axis that supports a horizontal film-feeding dish, a winding axis that supports a reel which winds up the film, and a suitable motion-transmitting device which makes the two axes rotate with the same angular velocity, the motion being transmitted from the winding axis to the feeding axis.

In operation the function of the apparatus is such that when the coil of the film to be projected is layed on the film-feeding dish, and its interior end is passed through the projector and fastened to the winding reel, and when the projection is begun, the film-feeding dish executes such a rotation that the film coil is not disordered, and at the end of the projection the film retakes accurately its original state that prevailed before the projection.

The purpose of the apparatus is to avoid the trouble of rewinding the film and also the damage of the film caused by rewinding by means of the simplest possible mechanism and manipulation.

The figures represent a practical embodiment of the invention. Fig. 1 is the right-hand view of the whole apparatus; Fig. 2 the back view of the apparatus; Fig. 3 the plan of the motion-transmitting device and the part that holds the winding reel; Fig. 4 a section taken on the line *a—b* of the parts shown in Fig. 3; and Fig. 5 a figure illustrating the axial part of the winding reel.

In the figures, 1 is the film coil; 2 the body of the case for preserving the film, at the same time serving as the feeding dish; 3 the stand for holding the feeding dish; 4 the feeding axis or shaft to which the stand 3 is attached; 5 a bevel-gear facing downward that forms the lower end of the feeding axis; 6 the bearing of the feeding shaft which keeps the axis thereof in the vertical direction; 7 the winding reel; 8 the part that holds the winding reel; 9 the pulley for rotating the winding shaft about its axis; 10 the bearing of the winding shaft; 11 and 12 bevel gears of the same form and size as 5, facing toward left and right respectively; 13 the winding shaft to which 8, 9, 11 and 12 are fixed; 14 the supporting rod of the entire apparatus, which continues to the bearing 10 of the winding axis at its rear end, and which supports the sliding lever 17 which continues to the bearing 6 of the feeding axis, by means of the branch rods 15 and 16. The sliding lever 17 is pivoted at a point 18

of the branch rod 15, and rests upon one of the three dents formed on the second branch rod 16, shown in Fig. 4. When it rests upon the middle dent, the bevel-gear 5 facing downward is not interlocked with the other gears, and the feeding dish can be rotated freely by the hand, but when it rests on the right or left dent, the gear 5 is interlocked with the gear facing left 11 or with that facing right 12, and the feeding shaft is rotated with the same angular velocity as that of the winding shaft due to the relation between gears stated above.

The holder 8 of the winding reel consists of a cylinder 21 which has a number of stopping nails 20 that can be made to appear and disappear by turning the knob 19, and of a number of elastic pressing pieces 22 which lie parallel to the axis of the circular cylinder around it; and the winding reel 7 consists of a bushing 23 which fits to the outer surface of the cylinder 21, and of a circular disc 25 which is fixed to one end of the bushing 23 to form a flange, and which has a number of holes 24 adjacent the bushing 23 to permit the springs 22 pass freely therein.

Referring to Figure 1, 26 and 27 are the film-hangers by which the part of the film to be fed is suspended; 28 is the sprocket-wheel for forwarding the film, which forms a part of the projector; 29 is the ordinary device of giving intermittent motion to the film; 30 is a cover attached to the winding reel so as to avoid the collapse of the wound film coil; 31 is a belt to rotate the winding pulley 9.

In use of the present apparatus, an empty reel 7 is first put on its holder 8 so that the spacing pieces 22 penetrate into the holes 24; the lid of the case for preserving film is taken away, and the body of the case together with the film-coil contained therein is placed on the stand 3; the interior end of the film coil is moved from the coil, and the film suspended on the film-hangers 26 and 27; then after being passed around the sprocket-wheel 28, the intermittent mechanism 29, and again around the sprocket-wheel 28, the end of the film is arranged under one of the spring pieces 22, the film going over the rest of the pieces as shown in Fig. 5; and in this way the connection between the film and the winding reel is effected; the cover 30 is put on the winding reel; the knob 19 is turned so that the stopping nails 20 fix the reel 7 and its cover 30 in their position. The bevel-gear 5 facing downward is ordinarily interlocked with the gear 11 facing left. When the projection is begun, the reel receives torque from the belt 31 and

winds up, the part of the film which has passed the projector. At the same time the belt transmits its angular velocity of rotation to the feeding dish. But the length of the film wound up 5 in a unit of time must be equal to that sent out from the dish in the same time during projection, and the inner radius of the film coil is initially equal to the outer radius of the cylinder of the winding reel, because the coil is what was 10 taken off from the same reel after the preceding projection. So that, although the quantities of the film in the two coils change with the progress 15 of projection, the relation provides that the outer radius of the winding coil always remains the same as the inner radius of the feeding coil. Therefore the fact that the two reels rotate with the same angular velocity satisfies the condition, described above, that the lengths of the film sent out and wound up in a unit of time must be 20 equal to each other; and hence no disorder takes place in any part of the film. This is the main feature of the invention.

When the projection is ended, the stopping 25 nails 20 are depressed by turning the knob 19; the reel 7 and its cover 30 are taken off together from the winding shaft and put on the table with the cover side up; then the cover itself is removed, and the empty body of the film case is taken down from the stand 3, put over the reel 30 on the table upside down, and the whole is turned up as a unit. In that case the film coil goes into the case freely, because the aggregate of the 35 spring pieces of the reel holder forms a larger circle than the bushing of the reel itself, and the initial part of the film wound around the aggregate forms a free ring which does not stick to the cylinder when the reel is taken apart from the aggregate. The case now containing the film may either be preserved with the lid put on, or may be used for a repeated projection. Thus 40 the film coil is brought to its initial state without any process of rewinding. This is the merit of

the present invention, and attention may be specially called to the fact that the coil obtained in the above manner is arranged in the same manner as that before the projection.

In the case the projection must at once be stopped, the bevel-gear 5 can be displaced to the central free position, the feeding dish be turned by the hand so as to unwind any excessive twist, then the bevel-gear can be interlocked with the gear 12 facing right which is not used ordinarily, and then the projection is to be started anew.

What is described above is a concrete example of the present invention, and the construction of all its parts may be changed in many ways without departing from the scope of the invention.

What I claim is:—

In cinematographic film winding apparatus, a winding shaft, means for rotatably supporting said winding shaft, a cylinder having stopping 20 nails fitted to one end of the shaft, elastic pressing pieces circumferentially arranged around the cylinder and extending parallel to the axis of the shaft, a film winding reel provided with 25 holes for receiving the nails and the elastic pressing member mounted on said cylinder, a pair of bevelled gear wheels mounted face to face in a spaced relation on the other end of the shaft, a vertical shaft, a film feed disk secured to said vertical shaft, a bevelled gear mounted on said 30 vertical shaft adjacent said pair of bevelled gears, a bearing for said vertical shaft, a pivotably mounted lever connected to said bearing so that movement thereof will cause engagement of the bevelled gear carried by the vertical shaft with 35 one gear wheel of said pair, and means for guiding the film from the feeding disk to the projecting apparatus whereby the film may be wound on said reel after leaving said projecting apparatus when said first mentioned shaft is rotated.

TAKEO SHIMIZU.
